(57) **CLAIM**

The ornamental design for "pendant light body," as shown and described.

DESCRIPTION

FIG. 1 is a perspective view of a pendant light body in accordance with our new design;

FIG. 2 is a front elevation view thereof, the rear elevation view and left and right side elevation views being identical thereto;

FIG. 3 is top plan view thereof;

FIG. 4 is a bottom plan view thereof; and,

FIG. 5 is a reference view showing the pendant light body in a first exemplary state of use.

Subject matter shown in dashed lines is for environmental purposes only and forms no part of the claimed invention.
